(57) **CLAIM**

The ornamental design for a vehicle grille, as shown and described.

DESCRIPTION

FIG. 1 is a front right perspective view of a vehicle grille according to the present invention.

FIG. 2 is a front left perspective view of the vehicle grille shown in FIG. 1.

FIG. 3 is a rear left perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a front right view of the vehicle grille shown in FIGS. 1-10, with the vehicle grille mounted on a vehicle, and the rest of the vehicle shown in de-emphasized and half-tone portions to illustrate environmental structure, which portions form no part of the claimed invention.

More particularly, in FIG. 11, the inventive vehicle grille is shown within the broken line, and the elements shown outside the broken line form no part of the claimed invention, but are instead included to show environmental aspects thereof.

In FIG. 11, the smaller broken line located inside the grille, in a circular badge shape, represents an unclaimed boundary and forms no part of the claimed design. This smaller broken line is also included in FIGS. 1, 2, 5, and 9, for the same reasons.
